LATCHING ASSEMBLY FOR VEHICLE SEAT FOOD TRAY

Harry Mendell Smith, Colorado Springs, Colo., assignor
to AMI Industries, Inc., Colorado Springs, Colo.

Filed Aug. 14, 1973, Ser. No. 388,221

Term of patent 14 years

Int. Cl. D8—07

U.S. Cl. D8—109

FIG. 1

FIG. 2

FIG. 3

FIG. 4

FIG. 5

FIG. 1 is a front and left side perspective view of a latching assembly for vehicle seat food tray showing my new design;

FIG. 2 is a bottom plan view;

FIG. 3 is a right side elevational view;

FIG. 4 is a top plan view; and

FIG. 5 is a rear elevational view.

I claim:

The ornamental design for a latching assembly for vehicle seat food tray, substantially as shown and described.
